UNITED STATES PATENT OFFICE

HORACE W. THOMPSON, OF CLEVELAND HEIGHTS, OHIO, ASSIGNOR TO LOVELL MANUFACTURING COMPANY, OF ERIE, PENNSYLVANIA, A CORPORATION OF PENNSYLVANIA

WRINGER

Application filed April 12, 1928. Serial No. 269,368.

This invention is designed to improve clothes wringers provided with quick-release devices. Such devices have commonly been supplied with some sort of a handle by means 5 of which the release might be operated. These handles have been arranged so that in set position they were parallel with the wringer. As a consequence in order to save expense the wringers have been shipped with 10 the release device in set position and in the ordinary use of the wringers in order to reduce the space occupied by the wringer it has been common for the operator to leave, or swing the release handle into position parallel 15 with the wringer top.

The result of this is to place the wringer roll when not in use, or during shipping under strain along one localized line at which the wringer is stopped. Inasmuch as these 20 wringers may be in stock for some time it leaves some impression on the roll.

According to the present invention the handle of the release device is arranged in set 25 position crosswise of the wringer frame and is in release position when the handle is swung parallel of the frame. In this way the wringer fully assembled may be shipped with the handle occupying the most limited space without putting the rolls under tension during 30 this period and the operator in using the wringer ordinarily swings the handle to parallel position and thus will leave the rolls without strain between periods of use. Features and details of the invention will appear 35 from the specification and claim.

A preferred embodiment of the invention is illustrated in the accompanying drawings as follows:—

Fig. 1 shows a front elevation, partly in 40 section, of a wringer.

Fig. 2 a section on the line 2—2 in Fig. 1, the parts being enlarged.

Fig. 3 a section on the line 3—3 in Fig. 2.

Fig. 4 a detached view of one of the fittings.

1 marks the wringer frame, and 2 and 3 the bottom and top rolls respectively. Bearings 4 and 5 are provided for shafts 6 and 7 of the rolls 2 and 3 respectively. It will be understood that similar bearings are arranged in the opposite ends of the rolls. The

upper bearings 5 are slidably mounted in side stiles 8 and a spring 9 rests on these bearings. The top bar 10 connects the side stiles. A release fitting 11 is secured at the center of this cross bar. It has a central opening 12, slots 13 extending axially through it and cams 14 leading from the slots 13 to positions at 90° from the slots.

A pin 15 is secured in a spring seat 16, this seat being secured to the center of the pin. 60 The pin has screw threads 17 by means of which it may be adjusted in a sleeve 18. The sleeve 18 extends through the opening 12 and is provided with shoulders 19 at its lower end which are of a shape and size to permit them 65 to pass through the slots 13. A handle 20 is secured to the upper end of the sleeve 18.

With the handle placed across the frame, as shown in the drawings, the shoulders 19 are swung to a position at 90° from the slots 70 13 and operating on the cams 14 put tension on the rolls. When the handle is swung to a position parallel to the frame the shoulders 19 are brought into register with the slots 75 13 thus permitting an upward movement of the sleeve 18 and with it the spring 9, thus relieving pressure on the rolls.

The general plan of this release device is illustrated in the reissue patent to Misner, 80 #15,865, June 24th, 1924.

What I claim as new is:—

In a wringer, the combination of a frame having a top bar; rolls in the frame; a tension spring arranged under the top bar and having its ends exerting pressure on the rolls; 85 and a quick releasing device for the tension means comprising a handle extending crosswise of the top when in set position and swinging toward a position parallel to the top to release the tension means, said swinging 90 motion permitting the handle to be brought into parallel with the top bar.

In testimony whereof I have hereunto set my hand.

HORACE W. THOMPSON. 95
